UNITED STATES PATENT OFFICE.

HENRY R. SHIRK, OF ALBION, INDIANA.

MEAT-CHOPPING MACHINE.

SPECIFICATION forming part of Letters Patent No. 268,298, dated November 28, 1882.

Application filed July 11, 1882. (No model.)

To all whom it may concern:

Be it known that I, HENRY R. SHIRK, of Albion, in the county of Noble and State of Indiana, have invented a new and Improved 5 Meat-Chopping Machine, of which the following is a full, clear, and exact description.

My invention relates to that class of meat cutting or chopping machines in which spring-supported knives and a revolving block are 10 used, the knives and block being operated by means of a sprocket-shaft; and my invention consists in the peculiar construction and arrangement of parts, as hereinafter fully described, and pointed out in the claims.

Reference is to be had to the accompanying 15 drawings, forming part of this specification, in which similar letters of reference indicate corresponding parts in all the figures.

Figure 1 is a side elevation of my improved 20 meat-chopping machine. Fig. 2 is a plan view thereof. Fig. 3 is a front elevation, and Fig. 4 is a sectional elevation taken on the line *xx* of Fig. 2.

A represents the block upon which the meat 25 is chopped; *B*, the sprocket-shaft, which is provided with the crank-wheel *a* at one end and the crank *b* at the other. *C C* represent the springs, which are held in the shaft *F*, and carry the knives *d d* at their outer ends, and 30 which are attached thereto by the bolts *e e*. *D* represents the stiffener, and *E E* represent the pawls for revolving the block *A*. The frame in which all of these parts are held in proper relation to each other for operation is 35 composed of the four posts *G*, extended plates *H H* at the top of the posts, the lower cross-pieces, *I I*, and upper cross-pieces, *J J*, extending from post to post at the ends of the frame, and the central cross-piece, *K*, attached 40 to the lower cross-pieces, *I I*, upper central cross-piece, *L*, attached to cross-pieces *J J*, and the side elevated cross-piece, *M*. (Shown clearly in Fig. 2.)

N is the central stud, upon which the block 45 *A* is secured, which stud passes through the upper central cross-piece, *L*, and rests at its lower end upon the lower central cross-piece, *K*, and forms the pivot for the block. The lower end of this stud has the metal cap *o*, 50 which is centrally socketed to rest upon the

pointed screw-bolt *p*, which passes up through the lower central cross-piece, *K*, and serves as the step or bearing-point for the stud *N*, and as a means for adjusting the block vertically to keep it at all times at the proper height to suit 55 the knives.

The sprocket-shaft *B* is journaled in the forward extensions of the upper plates, *H H*, of the frame, as shown in the drawings, and the projections *h h* thereof are arranged spirally 60 upon the shaft, as shown clearly in Figs. 2 and 3, and are adapted to lift the forward ends of the springs *C C* as the shaft is revolved, for causing the knives to deliver their blows for cutting any meat or other material placed upon 65 the block *A*, the springs *C* being held by the cross-bar or stiffener *D*. This stiffener is eccentric in form in cross-section, and is provided with the pins *c c*, which come between the springs *C C*, as shown clearly in Fig. 2, and 70 serve as guides to keep the springs in place. The outer end of the stiffener is provided with the crank or lever *D'*, by which the stiffener may be turned and held by means of the pin *d'* and perforated plate *d* in different positions 75 for regulating the force of the springs to correspond with the quantity and quality of the material being cut upon the block.

The pawls *E E*, by which the block *A* is revolved, engage with the ratchet *f*, formed 80 around the lower edge of the block, and are simultaneously operated by means of the vertical shaft *O*, which is rocked from the shaft *B* by means of the arm *p'* and connecting-rod *p''*, the pawls being attached to the bell-crank 85 *P*, secured upon the said vertical shaft *O*. The arm *p'* is by preference made integral with the rock-shaft *O*, and is formed with a series of perforations, as shown at *i* in Fig. 2, for regulating the motion of the block, which may be 90 done by moving the connecting-rod *p''* nearer to or farther from the shaft, as will be clearly understood. Upon the block is secured the sheet-metal rim *Q*, which is made vertically adjustable upon the block by means of the 95 screws *e'*, which secure the rim upon the block.

The keeper *j*, in which one end of the stiffener *D* is placed, forms a continuous bearing for the stiffener, while the keeper *j'* is only a partial keeper or hook, under which the stiff- 100

ener is placed, which keeps it from backward and upward movement, but leaves the stiffener free to be moved forward from under the hook or keeper j' , so that stiffener may be removed when it is desired. When the stiffener is removed the springs C C and knives d may be swung backward off from the block A, so that the meat or other material may be readily placed upon and removed from the block.

10 By this construction it will be seen that the chopper is made very simple, can be adjusted according to the material being cut, both in effect and the power required to operate the machine, and when the block becomes worn 15 so that it needs dressing off, I remove the rim and take off, say, one-half an inch from the chopping-surface of the block, and slip the rim down upon the block that distance, and raise the block that distance with the screw p below, 20 and then adjust the bell-crank P to correspond. In this manner it will be seen I can wear down the block to within three or four inches of the

bottom, thus making the machine very durable.

Having thus described my invention, what I 25 claim as new, and desire to secure by Letters Patent, is—

1. The combination, with the pivoted springs C, provided with knives d, of the eccentric cross-bar or stiffener D, journaled on the side 30 bars of the frame and provided with pins e, substantially as and for the purpose set forth.

2. The combination, with the adjustable block A, provided with the ratchet-teeth f, and the shaft B, of the vertical shaft O, provided 35 with the arm p' on its upper end, the bell-crank P, adjustably secured to the said shaft, the connecting-rod p'', and the pawls F, attached to the bell-crank, substantially as and for the purpose set forth.

HENRY R. SHIRK.
